UNITED STATES PATENT OFFICE.

MALON I. FLOWERS AND WILLIAM S. LYNCH, OF WAELDER, TEXAS.

GIN-SAW CLEANER.

1,140,669.

Specification of Letters Patent.

Patented May 25, 1915.

Application filed June 25, 1914. Serial No. 847,274.

To all whom it may concern:

Be it known that we, MALON I. FLOWERS and WILLIAM S. LYNCH, citizens of the United States, residing at Waelder, in the 5 county of Gonzales, State of Texas, have invented a new and useful Gin-Saw Cleaner, of which the following is a specification.

The device forming the subject matter of this application is a cleaner for gin saws, 10 and one object of the present invention is to provide a device so constructed that the saws may be cleaned while in rotation, and without removing the saws from the main frame.

Another object of the invention is to provide 15 novel means whereby a rotatable attrition element may be brought into and out of contact with the rotating gin saws.

It is within the scope of the invention to improve generally and to enhance the utility 20 of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made without 30 in the scope of what is claimed without departing from the spirit of the invention.

In the accompanying drawings:—Figure 1 shows in side elevation, a portion of a 35 gin equipped with the device forming the subject matter of this application; Fig. 2 is a vertical detail in section, parts being broken away; Fig. 3 is a plan of one of the disks which go to make up the attrition member; Fig. 4 is an elevation showing a 40 portion of the attrition member; Fig. 5 is an elevation showing a modified form of the attrition member; Fig. 6 is a plan of the disk used in that form of the invention shown in Fig. 5.

45 In the accompanying drawing the numeral 1 indicates the main frame of a gin, the frame being shown as relatively narrow, in order to economize space in the drawings. The frame 1 includes a longitudinally 50 slotted deck 2 ordinarily made up of slats as shown. Bearings 3 are mounted on the frame 1 and in the bearings 3 is journaled for rotation a main shaft 4 carrying gin saws 5. At one end, the main shaft 4 carries a pulley 6, about which may be passed

a belt 7, although the shaft 4 may be driven in any desired manner.

Mounted upon the lower portion of the main frame 1 are bearings 8 supporting for tilting movement an auxiliary frame the 60 same comprising a rock shaft 9 which is immediately journaled in the bearings 8. The rock shaft 9 supports side bars 10 and 11, the bars 10 and 11 being halved together as shown at 12, so that the auxiliary frame 65 may be extended longitudinally, the side bars 11 being slotted longitudinally as shown at 33 and the side bars 10 being provided with securing devices 14, such as bolt and nut structures adapted to hold the side 70 bars 10 and 11 against relative movement after adjustment.

Noting the point at which the reference character 15 is applied in Fig. 1 of the drawing it will be observed that the side 75 bars 10 and 11 are duplicated at one end of the shaft 9 and lie outside of the main frame 1. Extended across the main frame 1 and journaled in all of the bars 11 is a supplemental shaft 16. A short auxiliary shaft 17 80 is journaled in the side bars 10 which are duplicated at one side of the machine, as shown at 15. Mounted on the shafts 16 and 17 and located between the duplicated side bars are sprocket wheels 18 connected by a 85 sprocket chain 19. The shaft 17 carries a friction wheel 20 adapted to coöperate with the pulley 6 when the auxiliary frame is swung on its pivotal mounting 8—9. In order to secure a swinging movement in the 90 auxiliary frame, one of the side bars 10 is equipped with an upstanding handle 21. The auxiliary frame, when in an inoperative position lies in a position inclined with respect to the vertical, as shown in Fig. 2, and 95 the ends of the supplemental shaft 16 project beyond the side portions of the auxiliary frame and engage the rear bars 34 of the main frame to prevent the auxiliary frame from swinging rearwardly beyond a 100 predetermined angle.

Mounted on the supplemental shaft 16 are attrition elements which coöperate with the gin saws 5. These attrition elements may be of any desired form, but preferably 105 they comprise disks 22 disposed in abutment and in pairs, the disks having openings 23 which receive the shaft. Spacers or supports 24 surround the shaft 16 and lie between the pairs of disks 22. End blocks 110

23 surround the shaft 16 and abut against the outermost disks 22. Securing devices 26 pass through the spacers 24, the end blocks 25 and the disks 22, the disks 22 being provided with openings 27, which receive the securing devices.

The disks 22 are equipped with outstanding peripheral fingers 28. The fingers on the respective abutting disks may be disposed opposite to each other as indicated in Fig. 4, the fingers being arranged in diverging relation, as shown at 29.

In Figs. 5 and 6 a slight modification of the invention is shown, the disks being denoted by the reference character 30 and the fingers being shown at 31. In this form of the invention the fingers on the respective disks are not disposed opposite to each other, as shown in Fig. 4, but are arranged in alternating relation, as indicated at 32 in Fig. 5.

In practical operation, the auxiliary frame is swung upon its pivotal mounting 9, through the instrumentality of the handle 21, until the friction wheel 20 is brought into coöperation with the pulley 6. By this operation, the gin saws 5 will have been caused to enter between the fingers 28. When the shaft 4 is rotated, movement will be imparted to the pulley 6 and the pulley 6 will rotate the friction wheel 20, the latter driving the shaft 17 and motion being imparted to the shaft 16 through the medium of the sprocket wheels 18 and the sprocket chain 19. When the shaft 16 is thus rotated, the fingers 28 will engage with opposite edges of the gin saws 5 and remove cotton and gummy material therefrom. When the saws 5 have been cleaned sufficiently, the handle 21 is released and the auxiliary frame will swing gravitationally into the position shown in Fig. 2, the ends of the shaft 16 engaging the rear bars 34 of the main frame 1, to limit the rearward swinging movement of the auxiliary frame.

Having thus described the invention, what is claimed is:—

1. A gin saw cleaner embodying a main frame; a gin saw thereon; a vertically

swinging radius frame; a pivot element connecting the lower end of the radius frame with the main frame; and a cleaner upon the radius frame, the cleaner being movable with the radius frame toward and away from the saw in an arc of which the pivot element is the center, the radius frame comprising longitudinally extensible parts, and a connection between said parts, thereby to permit an adjustment in the radius of the arc in which the cleaner swings, and to position the cleaner for engagement with the saw, when the radius frame is swung.

2. A gin saw cleaner embodying a main frame; a gin saw thereon; a vertically swinging radius frame; a pivot element connecting the lower end of the radius frame with the main frame; and a cleaner upon the radius frame, the cleaner being movable with the radius frame toward and away from the saw in an arc of which the pivot element is the center, the radius frame being inclined with respect to the vertical to rest gravitationally in engagement with the main frame and out of operative relation with the saw; the radius frame embodying longitudinally extensible parts and a connection between said parts, thereby to vary the length of the radius frame and to maintain the cleaner out of engagement with the saw when the radius frame is swung into engagement with the main frame and out of operative relation to the saw.

3. A gin saw cleaner embodying a shaft; abutting disks on the shaft and equipped with peripheral, diverging fingers outstanding beyond the peripheries of the disks; supports engaging the outer faces of the disks and mounted on the shaft; and securing devices engaging the supports and the disks independently of the shaft.

In testimony that we claim the foregoing as our own, we have hereto affixed our signatures in the presence of two witnesses.

MALON I. FLOWERS.
WILLIAM S. LYNCH.
